UNITED STATES PATENT OFFICE.

GEORGE E. EVANS, OF WACO, TEXAS.

COTTON-BOLL EXTRACTING AND CLEANING DEVICE.

Application filed July 16, 1925. Serial No. 43,942.

This invention relates to new and useful improvements in cotton boll extracting and cleaning devices.

The object of the invention is to provide a device adapted to be connected in the air suction line leading to a cotton gin stand and arranged to extract burs from the cotton bolls as well as dirt and other extraneous matter, in an improved and efficacious manner.

10 A particular object of the invention is to provide means at the entrance to the device for dividing the air currents, whereby separate current lanes are provided above and below the cotton engaging elements; the currents in the lower lane carrying the burs and cotton into engagement with said elements and also conducting the burs and extraneous matter from the device; while the currents in the upper lane act to doff the cotton and conduct it to a point of discharge.

15

A further object of the invention is to so balance the upper and lower air currents that each will act independently of the other and counter draft or back lash will be substantially obviated.

Another object of the invention is to provide means in the lower air current lane cooperating with the saws of the cotton engaging elements, to deflect the lighter material into engagement with said saws and also permitting heavier matter, such as stones, bits of rock, nails and other extraneous material, to pass without contacting with the saws, thereby reducing the fire hazard.

25 A still further object of the invention is to provide a vertically adjustable bottom for the lower air current lane, whereby the said lane may be enlarged or restricted according to the condition of the cotton.

30 A construction designed to carry out the invention will be hereinafter described together with other features of the invention.

The invention will be more readily understood from a reading of the following specification, and by reference to the accompanying drawings, in which an example of the invention is shown, and wherein:

Fig. 1 is a longitudinal vertical sectional view of a device constructed in accordance 35 with my invention,

Fig. 2 is a transverse vertical sectional view taken on the line 2—2 of Fig. 1,

Fig. 3 is an enlarged transverse sectional view taken on the line 3—3 of Fig. 1,

Fig. 4 is an enlarged partial vertical sectional view of the air current control,

Fig. 5 is a detail of the deflector adjusting means,

Fig. 6 is a plan view of a portion of the adjusting links.

Fig. 7 is a sectional view of the bottom adjusting means,

Fig. 8 is a detail of the packing for the bottom,

Fig. 9 is an end view of a modified form, 65 a portion being in section, and

Fig. 10 is a partial longitudinal sectional view of another modification.

In the drawings the numeral 10 designates an elongated housing having side walls 70 11 and a stationary bottom 12 at its entrant end. At the said entrant end is connected a reduced air flue 13 through which the cotton and bolls are conveyed to the housing and in which a suitable boll breaker 14 is connected. A barrier and separating member in the form of a cylindrical screen 15 is mounted in the entrant end of the housing relatively above the flue and contiguous to the top of the housing.

80 A flare board 16 inclines from the flue up to the central portion of the surface of the screen and forms a throat. An air admitting duct 17 is formed above the flue and board 16 and has a door 18 hinged at its entrance (Fig. 4). The outward or closing movement of the door is limited by a transverse stop 19 and the door may be prevented from entirely closing by a set screw 21 threaded in a bracket 20. For closing the door an arm 22 depends from the door and has threaded therein an adjusting screw 24 connected to one end of a coiled spring 23 underlying the duct 17 and fastened at its opposite end to the housing. The spring 95 tends to close the door; while the suction in the housing and duct tend to open the door.

At its discharge end the housing is connected to the usual suction flue through which the cotton is conveyed to the gin stand. Transversely mounted saw members or drums 25 are disposed longitudinally of the housing in alternate relation to kicker rollers 26. These parts 25 and 26 constitute a train or series of cotton treating elements 105 and it will be noted that the drums and rollers are imperforate and are in such relation as to form a barrier or divider between the upper and lower portions of the housing, thereby producing a lower air lane and an upper air lane. Attention is also called 110 to the fact that the entrant end of the train

is nearer the top of the housing than the discharge end; thus the upper lane flares forwardly, reference being had to the direction of travel of the materials, while the 5 lower lane converges forwardly.

Between the screen 15 and the first kicker roll is mounted a wedge shaped deflector 27 having its smaller end close to the screen and its larger end concaved to receive the 10 kicker roller. This deflector has its longitudinal axis in line with the transverse axis of the screen so as to divide the air currents passing through the screen and deflect them into the upper and lower lanes.

15 The object of the foregoing structure is to separate the cotton from the burs and extraneous matter; to divert the cotton into the upper lane while the burs are retained in the lower lane and to conduct said materials along their respective lanes without 20 interference, one with the other. The particular construction of the drums 25 and the rollers 26 is not essential to the invention; however the drum illustrated has short saw 25 teeth pointed in the direction of rotation and disposed in circumferential rows on the drum (Fig. 2) and also spaced in comparatively close relation. The kicker rolls being set in advance of the drums and revolving in a clockwise direction need only to have short prongs or studs so as to knock from the teeth of the forward saws such burs and other material tending to pass to the upper lane. The teeth of the rear saws 30 will cast down any non-clinging material attempting to enter between said teeth and the rear sides of the rollers.

It will be apparent that the mass of cotton and burs entering through the flue 13 40 will expand in the throat and while a portion of the air currents will pass up through the screen to the upper lane, the remaining portion of the air currents and the cotton and burs will pass along the lower lane. 45 The screen 15 and deflector 27 will divert the cotton and burs into lower lane and the cotton will be caught up by the saw teeth and carried up into the upper lane where it will be doffed from the teeth and conducted along said lane which may thus be 50 called the "cotton" lane. The burs and extraneous matter such as nails, stones, stems, etc., will be conducted along the lower lane which for descriptive purposes may be 55 called the "bur" lane.

In order that the cotton may be properly acted upon I have found it advisable to obstruct the bur lane. To the forward end of the stationary bottom 12 and the deflector 60 27 I hinge an adjustable bottom 28 movable vertically between the side boards 11. Flexible packing strips 29 fastened to the side edges of said bottom (Fig. 8) exclude air so that the bottom may be adjusted without affecting the conducting air currents.

On the forward end of the bottom is a depending apron 30 at each end of which (Figs. 2 and 7) upright rack bars 31 are mounted. Pinions 32 fastened on a transverse shaft 33 engage said bars. A sprocket 70 wheel 34 is mounted on the outer end of the shaft and supports a sprocket chain 35. By suitably operating the chain the shaft is revolved and the bottom adjusted toward and from the train of cotton treating elements. 75

While the adjustable bottom will retard the passage, particularly toward the discharge end of the bur lane, additional means is usually required to deflect the cotton upward toward the saw teeth of the drum. For this 80 purpose I journal transverse rock shafts 36 in the bottom 28 and on each shaft arrange a plurality of closely spaced fingers 37 (Fig. 3) inclining forwardly under the drums 25. The fingers and shafts constitute combs and 85 the material will pass over the upper ends thereof and thus be deflected against said drums. The length of the fingers is controlled by the position of the respective drums.

90 In order to operate the combs in unison and easily, each rock shaft has near each end an arm 38 depending through a suitably packed slot 39 in the bottom 28. On each side these arms are connected by links 40 95 (Figs. 1, 3, 5, and 6) suitably bolted together at 41 and slotted so as to permit of relative adjustment. Adjacent the hinge of the bottom 29 a pair of gear segments 42 are mounted on said bottom concentric to the 100 first rock shaft 36. As is shown in Fig. 3 the arms 38' of this shaft have journaled therein a transverse shaft 43 to which the links are pivoted. Pinions 44 fastened on this shaft (Figs. 3 and 5) engage the segments and when the shaft is revolved said pinions travel on the segments thus swinging the arms 38' and the arms 38 by means of the links 40. By this means the inclination of fingers 37 is changed. For revolving 110 the shaft 43 a sprocket 45 mounted thereon is revolved by a chain 46 in any suitable manner.

At the discharge end of the housing I mount a second cylinder 47 with a barrier 48 115 extending toward the last drum 25. A flexible wiper 49 carried by the housing cleans the surface of the drum and prevents burs passing to the upper lane. A discharge spout 50 leads from the cotton lane and is 120 connected to the flue (not shown) leading to the gin stand. A hopper 51 depends from the housing and the bur lane leads to this hopper. At the bottom of the hopper I mount a transverse conveyor trough 52 having a screw conveyor 53. At one end the trough opens into a cylindrical box 54 having a revolving gate or dropper 55 arranged 125 to discharge the burs and other matter without admitting air. If desired the conveyor 130

and trough may be omitted and a box 54' and a gate 55' extended entirely across the bottom of hopper as is shown in Fig. 9.

It will be apparent that many modifications of the device may be made. In Fig. 10 I have a structure in which the drums 25 and kicker rollers 26 are omitted and in place thereof I use saw cylinders composed of circular saws 56 having spacer blocks 57 therebetween. Transverse division bars 58 are interposed between the saw cylinders. Ribs 59 fastened to bars pass between the saws immediately under the spacer blocks. This arrangement prohibits the passage of the burs into the cotton lane and functions the same as the drum and kicker roller form.

In operating the device the cotton is removed from the wagon or other storage in the usual manner by means of an air suction conveyor or flue. After passing through the boll breaker 14, which will crack and open the bollie cotton, the cotton and burs are conducted by the flue 13 to the entrance to the device. The movable parts of the device are driven in any suitable manner. As the cotton and burs enter the throat of the device they spread and a portion of the air currents pass up through the screen, the barrier 27 dividing the upper from the lower air currents.

The cotton and burs passing along the lower or bur lane are deflected into engagement with the saw teeth of the drums 25 by the fingers 37 of the combs. The drums and kicker rollers 26 being rotated in a clockwise direction will pick up the cotton and repel the burs. The cotton is carried into the upper lane and doffed from the saw teeth by the air currents. The burs and extraneous matter being cast down by the kicker rollers will pass over and through the combs. It is pointed out that the direction of travel of the air currents is substantially tangential to the tops and bottoms of the drums and the said rollers being smaller in diameter and being located therebetween but are spaced sufficiently from the drums to allow the upper and lower currents to equalize.

Each successive drum and kicker roller will repeat the operation until all of the cotton and burs are separated. The cotton will pass out through the spout 50 with the air currents from both lanes, the lower air currents passing through the screen 47. The burs, dirt, bits of rock and extraneous matter will pass into the hopper 51. The conveyor 53 will carry this material to the gate 55 which will discharge it.

If the material is passing too rapidly under the saws or is being unnecessarily retarded the operator merely has to operate the chain 46 to rotate the shaft 43 to operate the links 40 and change the inclination of the combs. Where the condition of the cotton requires a greater space to pass in the

lower lane, as where the bolls are damp and tough, the chain 35 may be operated to rotate the shaft 33 and pinions 32, thus swinging the bottom down and moving the fingers 37 from the saw drums.

In numerous instances the intake of air is cut off in advance of the flue 13 and when this happens the conveying of cotton will stop. For this reason the door 18 (Fig. 4) is provided. When the suction in the flue 13 is defeated the vacuum created will pull the door open against the tension of the spring 28. Just as soon as this condition is overcome the door will be released and will close or abut the screw 21. If it is desired to admit air to the upper or cotton lane so as to control the passage of cotton therethrough the screw 21 is adjusted to admit a certain amount of air.

By reason of the air admitted through the opening of the door 18, the suction in the flue 13 is of course reduced and therefore the quantity of cotton delivered to the device will be reduced.

Various changes in the size and shape of the different parts, as well as modifications and alterations may be made within the scope of the appended claims.

What I claim, is:

1. In a cotton boll extracting and cleaning device, an elongated housing, a train of cotton treating elements therein, an air barrier at the entrance diverting the air currents into lanes immediately above and below the treating elements and contiguous thereto, and means for separately discharging the cotton and burs from the device.

2. In a cotton boll extracting and cleaning device, an elongated housing, a train of cotton treating elements therein, an air barrier at the entrance diverting the air currents into lanes above and below the treating elements, means for separately discharging the cotton and burs from the device, and deflectors below the treating elements to deflect the cotton and burs toward the same.

3. In a cotton boll extracting and cleaning device, an elongated housing, a train of cotton treating elements therein, an air barrier at the entrance diverting the air currents into lanes above and below the treating elements, means for separately discharging the cotton and burs from the device, deflectors below the treating elements to deflect the cotton and burs toward the same, and an adjustable bottom carrying said deflectors.

4. In a cotton boll extracting and cleaning device, an elongated housing, a train of cotton treating elements therein, an air barrier at the entrance diverting the air currents into lanes above and below the treating elements, means for separately discharging the cotton and burs from the device, deflectors below the treating elements to de-

flect the cotton and burs toward the same, and means for simultaneously adjusting the deflectors.

5. In a cotton boll extracting and cleaning device, an elongated housing, a train of cotton treating elements therin, an air barrier at the entrance diverting the air currents into lanes above and below the treating elements, means for separately discharging the cotton and burs from the device, deflectors below the treating elements to deflect the cotton and burs toward the same, an adjustable bottom carrying said deflectors, and means for simultaneously adjusting the deflectors.

6. In a cotton boll extracting and cleaning device, a housing, a flue entering said housing, a screen adjacent the flue entrance, a barrier extending from the screen for diverting the air currents into upper and lower lanes extending forwardly in the housing, and cotton treating elements in the housing between the lanes for delivering the cotton to the upper lane and the burs to the lower lane.

7. In a cotton boll extracting and cleaning device, a housing, a flue entering said housing, a screen adjacent the flue entrance, a barrier extending from the screen for diverting the air currents into upper and lower lanes extending forwardly in the housing, cotton treating elements in the housing between the lanes for delivering the cotton to the upper lane and the burs to the lower lane, and means for separately discharging the cotton and the burs.

8. In a cotton boll extracting and cleaning device, a housing, a flue entering said housing, a screen adjacent the flue entrance, a barrier extending from the screen for diverting the air currents into upper and lower lanes extending forwardly in the housing, cotton treating elements in the housing between the lanes for delivering the cotton to the upper lane and the burs to the lower lane, and means for admitting air to the upper portion of the screen and above the flue entrance.

9. In a cotton boll extracting and cleaning device, a housing, a flue entering said housing, a screen adjacent the flue entrance, a barrier extending from the screen for diverting the air currents into upper and lower lanes extending forwardly in the housing, cotton treating elements in the housing between the lanes for delivering the cotton to the upper lane and the burs to the lower lane, a second screen at the end of the train of elements, an air and cotton outlet above the second screen, and a bur discharge below the second screen.

10. In a cotton boll extracting and cleaning device, a housing, a flue entering said housing, a screen cylinder adjacent and extending above said entrance, a throat in the

housing flaring to said screen, an air admitting duct above the flue and throat leading to the screen, a closure for said duct, an air barrier dividing the air currents passing from the screen into upper and lower conducting lanes in the housing, and means for delivering cotton to the upper lane and retaining burs in the lower lane. 70

11. In a cotton boll extracting and cleaning device, a housing, a flue entering said housing, a screen cylinder adjacent and extending above said entrance, a throat in the housing flaring to said screen, an air admitting duct above the flue and throat leading to the screen, a closure for said duct, an air barrier dividing the air currents passing from the screen into upper and lower conducting lanes in the housing, means for delivering cotton to the upper lane and retaining burs in the lower lane, and resilient 85 means for shutting the closure set to yield to a suction, whereby the closure is opened.

12. In a cotton boll extracting and cleaning device, an elongated housing having an entrance at one end and a discharge at the other end, a train of cotton treating elements dividing the housing into upper and lower lanes, and means for dividing entrant air currents and diverting them into the upper and lower lanes, said train of elements inclining toward the discharge end of the housing, whereby the upper lane flares forwardly and the lower lane converges forwardly.

13. In a cotton boll extracting and cleaning device, an elongated housing having an entrance at one end and a discharge at the other end, a train of cotton treating elements dividing the housing into upper and lower lanes, means for dividing entrant air currents and diverting them into the upper and lower lanes, said train of elements inclining toward the discharge end of the housing, whereby the upper lane flares forwardly and the lower lane converges forwardly, and a vertically adjustable bottom 110 under the lower lane.

14. In a cotton boll extracting and cleaning device, an elongated housing having an entrance at one end and a discharge at the other end, a train of cotton treating elements dividing the housing into upper and lower lanes, means for dividing entrant air currents and diverting them into the upper and lower lanes, said train of elements inclining 120 toward the discharge end of the housing, whereby the upper lane flares forwardly and the lower lane converges forwardly, a vertically adjustable bottom under the lower lane, and inclined deflectors in the lower lane of the housing directed toward the cotton treating elements.

15. In a cotton boll extracting and cleaning device, an elongated housing having an entrance at one end and a discharge at the 130

- other end, a train of cotton treating elements dividing the housing into upper and lower lanes, means for dividing entrant air currents and diverting them into the upper and 5 lower lanes, said train of elements inclining toward the discharge end of the housing, whereby the upper lane flares forwardly and the lower lane converges forwardly, a vertically adjustable bottom under the lower 10 lane, and inclined deflectors in the lower lane of the housing directed toward the cotton treating elements, each deflector comprising a plurality of spaced fingers.
16. In a cotton boll extracting and cleaning device, an elongated housing, a train of 15 cotton treating elements therein, means for diverting entrant air currents concurrently

into lanes immediately above and below the treating elements and contiguous thereto, and means for separately discharging cotton 20 and burs from the device.

17. In a cotton boll extracting and cleaning device, an elongated housing, a train of cotton treating elements in the housing, a cotton lane above the cotton treating elements, a bur lane below the said elements, means for admitting air currents to said lanes, and an air suction discharge at the end of the housing, said lanes having communication through the train of cotton treating 25 elements, whereby the air currents traveling above and below said elements are equalized.

In testimony whereof I affix my signature.
GEORGE E. EVANS.
